UNITED STATES PATENT OFFICE.

ALFRED SEARS, OF WORCESTER, MASSACHUSETTS; ALFRED F. SEARS ADMINISTRATOR OF
SAID ALFRED SEARS, DECEASED.

MECHANICAL MOVEMENT.

No. 921,629.

Specification of Letters Patent.

Patented May 11, 1909.

Application filed August 29, 1907. Serial No. 390,585.

To all whom it may concern:

Be it known that I, ALFRED SEARS, a citizen of the United States, residing at Worcester, in the county of Worcester and State of Massachusetts, have invented a new and useful Mechanical Movement, of which the following is a specification.

This invention relates to a mechanical movement which, while capable of general use, is especially useful for that class of machines in which a more or less heavy weight has to be lifted and lowered at times and held in its raised or intermediate positions. One example of such a use of the invention is in clothes driers, but it will be understood that there are many others.

The principal objects of the invention are to provide a simple, convenient and inexpensive construction, whereby a driven member can be rotated from the driving member, preferably of larger circumference, and each preferably being in the form of a wheel, in such a way that the driven member can be turned easily by the driving member, and so that the driven member will be securely locked against independent motion; that is, motion imparted to it in any way except by or through the driving member; also to provide a simplified construction for accomplishing these results; and to provide an arrangement which will be capable of other uses as will be explained hereinafter.

Reference is to be had to the accompanying drawings which form part of this specification, and in which—

Figure 1 is a front elevation of a clothes drier showing how one form of this invention may be applied thereto. Fig. 2 is a sectional view of the same on the line 2—2 of Fig. 1. Fig. 3 is a front elevation of a stationary standard on the clothes drier for supporting certain operating parts. Fig. 4 is a front elevation of the driving member with the driven member removed therefrom. Fig. 5 is a front view of the driven member. Fig. 6 is a vertical sectional view of the driving and driven members with the parts located adjacent thereto, and Fig. 7 is a similar view showing a slight modification.

While the drawings show a clothes drier, it will be understood that the invention is applicable to any ordinary machinery in which one part 10 is in fixed position, and another part 11 is intended to be raised and lowered either by hand or machinery. In

the present case the stationary part 10 is shown as provided with a bracket 12 which extends up a certain distance and is provided with a fixed stud 13. On this stud is journaled the driven member 14 which has a hub 15 extending to the rear of the stud. The driven member is held on the stud by a cotter pin 16, or in any other desired manner. This driven member is shown in the form of a sheave, over which passes a belt, cord, or chain 17, the latter being connected with a sheave 18 on the movable member 11 on the machine to which the invention is applied. In the present case the flexible connection 17 is secured to the web of the sheave through perforations therein, and is intended to be wound upon the same as upon a drum. On the back of the driven member, or located in any other position so as to rotate therewith, are a series of projections 20 preferably cast integral with the driven member, which will be described hereinafter.

Mounted to rotate on the hub 15 is the driving member 21. This driving member itself consists of an ordinary sheave or pulley over which passes a flexible connection 22 in the form of a cable, chain, or cord. This flexible connection passes between pulleys 23 on a bracket 24, and extends down between these pulleys into such position that it may be readily operated from below. But it will be understood that it may be operated in any desired way, and in fact, both of the sheaves are illustrated merely to show a practical embodiment of the invention, as any other power transmitting mechanism can be substituted therefor.

Fixedly connected with the driving member, and preferably secured to the face thereof is an eccentric 25. In the present instance, the eccentric and driving member are provided with a perforation 26 fitting the hub 15, so that both of these parts, being fixed together, are journaled on this hub.

Mounted to turn freely on the eccentric is a toothed wheel 27 having an arm 28 secured thereto and extending beyond the periphery of the driving member. This toothed wheel is provided with a smaller number of teeth 29 than is the number of projections 20, and the teeth are intended to mesh with these projections, as the toothed member gyrates on the eccentric during the rotation of the latter. It is intended that the arm 28 be held in fixed position in ordinary operations by means of a

cleat 30 or in any other desired way. When the parts are constructed in this way the rotation of the wheel 21 causes the eccentric to turn and the toothed wheel to gyrate or move in an orbital path. This path is such that as it moves about it will engage successively the cylindrical projections 20 and rotate the wheel 14 at a slower rate of speed than that at which the wheel 21 moves and 10 in the same direction. On account of the curved sides and general triangular shape of the teeth 29, the cylindrical projections 20 move along them easily without excessive friction. It will be seen that this manner of 15 transmission of power is very efficient, as very little power imparted to the wheel 21 will exert considerable power on the wheel 14 with a corresponding reduction in speed. Moreover the fixing of the arm 28 prevents 20 any motion being imparted to the toothed wheel, and from that to the eccentric by the wheel 14. In other words, the latter wheel is locked against any motion, except that coming to it from the rotation of the wheel 21. 25 This is assisted by the shape of the teeth 29 and projections 20. On account of this it will be seen that if in lifting the movable member 11, there should be any breakage, or if the flexible member 22 should be accidentally 30 released, the movable member cannot drop. This is of use in many different arts, as will readily be understood.

Another way in which the device can operate for other purposes is to fix the wheel or 35 member 14, either by holding it by hand or otherwise leaving the arm 28 free, then the rotation of the wheel 21 will cause the arm to rotate at a slower rate of speed in the opposite direction, but the difference in speed 40 will not be as great as is the case when the device is set up as described above. In order to take advantage of the latter operation, it will be understood by any skilled mechanic that a wheel 270 or any other mechanical 45 element may be substituted for the arm 28, as is indicated in Fig. 7 and an arm 140 can be substituted for the wheel 14 and held against rotation as by a pin 141. The only motion possible is through the operation of 50 the main wheel 21. It will be seen that these results are obtained in a most simple and convenient manner by the use of very few parts, such parts being of such a nature as to

be made of castings requiring very little machining in manufacture, and being so constructed and put together that there is very little probability of their getting out of order in use. 55

While I have illustrated and described a preferred form of the invention and set forth certain ways in which it may be utilized in practice, I am aware that many modifications may be made therein by any person skilled in the art, either to apply it in the same way, or to apply it to the many different uses to which it is adapted without departing from the scope of the invention as expressed in the claims. Therefore, I do not wish to be limited to the particular form shown or use described, but 65

What I do claim is:— 70

1. In a mechanical movement, the combination of a fixed support, a stud projecting therefrom, a wheel having a hollow hub loosely mounted on said stud, a driving member journaled on said hub adjacent to the face of said support, an eccentric on the driving member, and a toothed wheel eccentrically mounted with respect to the hub, said first named wheel having a series of projections for engaging the teeth of the toothed wheel. 75

2. In a mechanical movement, the combination of a support, a stud projecting therefrom, a wheel having a hollow hub journaled on said stud, a driving member journaled on said hub, a toothed wheel eccentrically mounted with respect to the hub adjacent to the face of the wheel and engaging the driving member, said wheel having a series 80 of projections for engaging the teeth of the toothed wheel, and means whereby said first named wheel may be held against rotation whereby the toothed wheel will be rotated by the rotation of the driving member, but 85 in the opposite direction, and the driving member cannot be rotated by the rotation of the toothed wheel. 90

In testimony whereof I have hereunto set my hand, in the presence of two subscribing 100 witnesses.

ALFRED SEARS.
